Specification for Design.

Patented Apr. 13, 1920.

Application filed July 7, 1919. Serial No. 309,241. Term of patent 3½ years.

To all whom it may concern:

Be it known that I, ROBERT BOOTH, a subject of Great Britain, residing at New Orleans, in the parish of Orleans and State of Louisiana, have invented a certain new, original, and ornamental Design for Automobiles, of which the following is a specification, reference being had to the accompanying drawings, forming a part thereof.

The figure represents a side elevation of an automobile showing my new design.

I claim—

The ornamental design for an automobile as shown.

In testimony whereof, I have signed my name to this specification in the presence of the subscribing witness.

ROBERT BOOTH.
